UNITED STATES PATENT OFFICE.

NICHOLAS WITSCH, OF JERSEY CITY, NEW JERSEY, ASSIGNOR TO THE AMERICAN LITHOGRAPHIC COMPANY, OF NEW YORK, N. Y.

DESIGN FOR A PRINT OR PATTERN FOR CIGAR-BOXES.

SPECIFICATION forming part of Design No. 26,188, dated October 13, 1896.

Application filed September 5, 1896. Serial No. 605,033. Term of patent 7 years.

To all whom it may concern:

Be it known that I, NICHOLAS WITSCH, a citizen of the United States, residing at Jersey City, in the county of Hudson and State 5 of New Jersey, have invented and produced a new and original Design for a Print or Pattern for Cigar-Boxes; and I do hereby declare the following to be a full, clear, and exact description of the same, reference being had to 10 the accompanying drawing, forming a part thereof.

The design is placed upon a cigar-box, as shown in the drawing.

Said design comprises the American flag, a 15 shield having stars and bars corresponding in color to said flag, an eagle with spread wings mounted upon said shield, and sprays of palm.

The flag is mounted upon a staff passing obliquely across the design, having cords and tassels hanging from its upper end. The flag 20 hangs downwardly and its free end is festooned and forms a background for the shield. The palms are arranged at the fold of the flag and to the right of the shield and eagle.

I claim—

The design for an ornamental print or pattern for cigar-boxes, substantially as shown and described.

In testimony whereof I affix my signature in presence of two witnesses.

NICHOLAS WITSCH.
